UNITED STATES PATENT OFFICE.

WILLIAM RUNGE, OF SENECA FALLS, NEW YORK, ASSIGNOR TO THE SENECA FALLS MANUFACTURING COMPANY, OF SENECA FALLS, NEW YORK.

DRILLING AND TAPPING ATTACHMENT FOR DRILL-PRESSES, &c.

SPECIFICATION forming part of Letters Patent No. 687,407, dated November 26, 1901.

Application filed February 4, 1901. Serial No. 45,977. (No model.)

To all whom it may concern:

Be it known that I, WILLIAM RUNGE, a citizen of the United States, residing at Seneca Falls, in the county of Seneca and State of New York, have invented new and useful Improvements in Drilling and Tapping Attachments for Drill-Preses and other Machines, of which the following is a specification.

This invention relates to a drilling and tapping attachment which is more particularly designed for drill - presses and similar machines in which the driving-spindle turns constantly in the same direction.

One of the objects of this invention is to provide a drilling and tapping attachment for machines of this character which contains a gage mechanism whereby the rotation of the tool-support will be automatically arrested when the same has made a predetermined number of turns and then permits the tool-support to be turned backwardly.

My invention also has the objects to provide means whereby the tool - support may be turned constantly in the same direction and to improve the mechanism in other respects.

In the accompanying drawings, consisting of two sheets, Figure 1 is a sectional elevation of my improved drilling and tapping attachment, taken in line 1 1, Fig. 8, showing the position of the parts when the tap or thread-cutting tool begins to cut a thread. Fig. 2 is a sectional elevation of the same in line 2 2, Fig. 8, showing the position of the parts when the tap has completed the thread. Fig. 3 is a sectional elevation at right angles to Figs. 2 and 3 in line 3 3, Fig. 8, and showing the position of the parts when the tap begins its backward movement. Fig. 4 is a fragmentary front view of the attachment, showing the dial whereby the gage mechanism may be set for cutting a predetermined number of threads. Fig. 5 is a fragmentary vertical section in line 5 5, Fig. 1, showing the clutch whereby the tool is turned forwardly.

Fig. 6 is a similar section in line 6 6, Fig. 3, showing the clutch whereby the tool is turned backwardly. Figs. 7, 8, and 9 are horizontal sections in lines 7 7, 8 8, and 9 9, Fig. 2, respectively. Figs. 10, 11, and 12 are fragmentary vertical sections in lines 10 10, 11 11,

and 12 12, Fig. 8, respectively. Fig. 13 is a detached sectional view of the worm-wheel forming part of the gage mechanism. Fig. 14 is a detached perspective view of the clutch-pawl forming part of the gage mechanism. Fig. 15 is a fragmentary vertical section in line 15 15, Fig. 7. Fig. 16 is a fragmentary sectional elevation of the shipper-rod and the parts connected therewith. Fig. 17 is a fragmentary sectional elevation of the return-shaft and the parts connected therewith. Fig. 18 is a horizontal section in line 18 18, Fig. 1. Fig. 19 is a fragmentary section similar to Fig. 10, on an enlarged scale, showing the position of the clutch-pawl when the gage mechanism is not in operation.

Like letters of reference refer to like parts in the several figures.

A represents the vertical driving-spindle of a drill-press, to the lower end of which my improved drilling and tapping attachment is secured. This spindle is turned constantly forward and is capable of being moved axially up and down by suitable mechanism.

B represents the casing or supporting frame of the drilling and tapping attachment, which is closed at its upper end by a fixed head b and at its lower end by a removable head b'.

C represents a vertical driving-sleeve which is journaled in a bearing c in the upper head of the casing and which is provided at its upper end with a flange or shoulder c', bearing against the upper end of the bearing c. To the upper end of the driving-sleeve is secured a coupling shank or spindle c², which is detachably secured in a socket a in the lower end of the driving-spindle of the drill-press in the usual manner. The coupling-shank and driving-sleeve are preferably connected by means of an external screw-thread formed on the lower end of the shank and engaging with an internal screw-thread in the upper end of the driving-sleeve, as shown in Figs. 2 and 3.

D represents the upright tool-supporting spindle, which is arranged in the lower head of the casing and extends with its upper end into the driving-sleeve C, while its lower end is provided with a chuck or socket d, in which a screw-cutting tap d' or other tool is secured.

E represents a thrust-collar which is secured by a screw connection to the tool-spindle and against the upper side of which the lower head of the casing is adapted to bear 5 for applying pressure upon the tool during the forward or cutting movement of the same.

The mechanism whereby the forward or operative movement of the tool is produced is constructed as follows:

- 10 F represents an intermediate driving friction-disk which is arranged between upper and lower driven friction-disks F' F². The frictional contact between these opposing disks is preferably increased by interposing facings f, of fiber, leather, or similar material, 15 between these disks, as shown in Figs. 2 and 3. The upper friction-disk is secured by a screw-joint with the central part of the tool-spindle. The lower friction-disk is arranged on the upper 20 end of an adjusting-sleeve G, which latter is capable of sliding lengthwise on the tool-spindle, but is compelled to turn therewith by a spline or key connection g. The lower end of the adjusting-sleeve G is arranged within the 25 thrust-collar and bears against an upwardly-facing shoulder e in the collar, as shown in Fig. 2. Upon screwing the thrust-collar up or down on the tool-spindle the lower friction-disk, which rests by means of the adjusting- 30 sleeve on the thrust-collar, is raised or lowered. By this means the frictional contact between the disks F F' F² may be varied according to the size of the tool which is used and permits the driving-disk to slip on the driven 35 disks when the tool encounters a resistance greater than the tool is capable of withstanding, thereby avoiding breaking of the tool. When a heavy tool is used, the lower friction-disk is raised, so as to increase the grip between 40 the disks, whereby the forward movement of the tool will only be arrested when the tool encounters considerable resistance—for instance, when the tool strikes the bottom of the hole in which it is cutting a thread. 45 When a small tool is used, the lower friction-disk is lowered, so as to reduce the frictional contact between the disks, whereby the rotation of the tool will be arrested when it encounters a comparatively small resistance— 50 for instance, when striking a hard place in the hole of the article which is being tapped.

The thrust-collar is preferably turned for adjusting the friction between the disks and is held in position after adjustment by a worm 55 e', which is journaled transversely on one side of the thrust-collar and meshes with worm-teeth e² on the adjacent part of the adjusting-sleeve, as shown in Figs. 2, 3, and 18. One end of the worm projects beyond the 60 outer side of the thrust-collar and is provided with a finger-piece or knob e³ for turning the same. The worm and worm-teeth not only serve to turn the thrust-collar, but also serve to connect the thrust-collar and adjusting- 65 sleeve, so that these parts move up or down together.

H represents an annular flange or rim which

projects upwardly from the outer edge of the intermediate friction-disk F, and i is a supporting-ring which is connected by a screw-joint with the upper edge of said flange. 70

J represents a driven clutch-disk which is mounted loosely on the upper part of the tool-spindle between the supporting-ring i and the driving-sleeve C. The under side of the 75 clutch-disk J is provided with one or more recesses j, which receive guide-pins j', projecting upwardly from the supporting-ring i, as shown in Fig. 2, whereby the clutch-disk and driving friction-disk are compelled to 80 turn together; but the clutch-disk is capable of moving axially up and down on the tool-spindle independent of the driving friction-disk. The upward movement of the driven clutch-disk with reference to the driving 85 friction-disk is limited by stops or screws j², arranged in openings in the driven clutch-disk J and secured at their lower ends to the supporting-ring i, as shown in Fig. 3, while the heads at the upper ends of the screws 90 are adapted to bear against shoulders j³ in said openings.

K represents a driving clutch disk or wheel which is secured to the lower end of the driving-sleeve C by a screw-joint or otherwise 95 and bears against the lower end of the bearing c, in which the driving-sleeve is journaled. The under side of the driving clutch-disk is provided with one or more coupling-pins k', which are adapted to engage with 100 the side of coupling-pins k², arranged on the upper side of the driven clutch-disk J. The latter is held yieldingly in an elevated position, so that its pins are engaged by those of the driving clutch-disk, by springs k³, arranged 105 between the bottom of the recesses j in the driven clutch-disk J and the upper ends of the guide-pins j'.

During the normal operation of cutting a thread the frame or case bears downward on 110 the thrust-collar E and the clutch-disks J K are coupled, as shown in Figs. 1 and 5, whereby the rotation of the driving-spindle is transmitted successively to the coupling-spindle c², driving-sleeve C, upper clutch-disk K, lower clutch-disk J, supporting-ring i, driving friction-disk F, driven friction-disks F' F², adjusting-sleeve G, and tool-spindle D to the tap d', whereby the latter is turned forward. For the purpose of preventing the casing and the parts mounted 115 thereon from turning with the rotating parts, whereby motion is transmitted from the driving-spindle to the tap, the casing is connected by any suitable means with a stationary part 120 of the drill-press—for instance, by a chain b², which is connected at one end with the casing and at its other end with the drill-press standard in a well-known manner.

If at any time during the progress of cutting it is desired to stop the operation of the tool, the operator raises the driving-spindle, together with the casing and the parts mounted 125 thereon, whereby the upper or driving

clutch-disk K is lifted with its coupling pins k' out of engagement from the coupling-pins k^2 of the driven clutch-disk J, thereby arresting the forward movement of the tool.

5 For the purpose of producing a backward rotation of the tool or tap and causing the same to unscrew itself from the thread which it has cut, a mechanism is provided for reversing the movement of the tap, which is 10 o constructed as follows:

L represents a lower clutch gear-wheel, which is mounted loosely on the adjusting-sleeve G and journaled in a bearing l in the lower head of the casing. This wheel is held 15 against axial movement in its bearing by a screw l', arranged in the side of the bearing l and engaging with a peripheral groove l² in the hub of the clutch-wheel L, as shown in Figs. 1, 2, and 3. The latter is provided on 20 its upper side with coupling-pins l³, which are adapted to be engaged by coupling-pins l⁴ on the under side of the lower friction-disk F².

l⁵ is an upright tubular shaft which is 25 arranged in the side of the casing and journaled on an arbor l⁶, which is secured at its ends to the upper and lower heads of the casing, as shown in Figs. 2 and 17. The hollow shaft is provided at its upper end with a gear-pinion l⁷, which meshes with gear-teeth on the periphery of the driving clutch-wheel K, and at its lower end with a gear-pinion l⁸.

l⁹ is an intermediate gear-pinion which is 30 journaled on a pin or stud l¹⁰, secured to the lower head of the casing, and which meshes on one side with the gear-pinion l⁸ on the lower end of the shaft l⁵ and on its opposite side with the lower clutch gear-wheel L, as shown in Figs. 1 and 9. While the driving-spindle is turning forwardly the motion of 35 the latter is transmitted successively from the driving-wheel K to the upper gear-wheel l⁷, shaft l⁵, and pinions l⁸ l⁹ to the lower clutch gear-wheel L, whereby the latter is rotated in a direction opposite to that in which the driving-spindle is rotated. The lower clutch-wheel is rotated idly so long as the upper clutch-disks J K are coupled and the tool is 40 moved forward. Upon raising the casing and 45 the parts connected therewith sufficiently to bring the pins l³ of the lower clutch-wheel into engagement with those of the lower friction-disk F², as shown in Figs. 3 and 6, the driving-spindle is coupled with the reversing 50 mechanism. The reverse movement of the lower clutch-wheel L will now be transmitted successively to the lower friction-disk F², adjusting-sleeve G, and tool-spindle D to the tap, and the latter will be backed out of 55 the thread which it has cut.

In order to permit of automatically stopping the forward movement of the tap after the same or its actuating mechanism has made a predetermined number of turns, an automatic stop or gage mechanism is provided, 60 which is constructed as follows:

M represents an upright shipper-rod, which

is arranged in the front part of the casing and guided at its lower end in an opening in the lower head of the casing, while its upper end is guided in a thimble m, which is secured in the upper head of the casing, as shown in Fig. 16.

m' represents a shipper-fork engaging with an annular groove m² in the periphery of the driven clutch-disk and provided with an eye m³, which is screwed on the upper part of the shipper-rod and held in place thereon by a jam-nut m⁴. The driven clutch-disk J is free to turn independent of the shipper-fork 80 and rod, but this disk and the fork and rod are compelled to move up and down together. Upon moving the shipper-rod and fork downwardly, together with the driven clutch-disk, until the coupling-pins k² of the latter are 85 out of engagement from the coupling-pins k' of the driving clutch-disk the mechanism whereby the tap is moved forward is disconnected from the driving-spindle and the forward rotation of the tap ceases. 90

n is a rotating tappet or pin, which is adapted to engage with a trip shoulder or projection m⁵ on the shipper-rod. The projection m⁵ is arranged on a sleeve m⁶, which is secured on the shipper-rod between the under 95 side of the fork m' and a shoulder m⁷ on the shipper-rod, as shown in Fig. 16. The tappet n is arranged on the rear side of a tappet-wheel N, which is mounted loosely on a horizontal gage-shaft n'. The gage-shaft is normally geared by intermediate mechanism with the tap-support, so that this shaft turns forward and backward with the tap. The gearing for this purpose (shown in Figs. 1, 2, 7, and 8) consists of a worm-wheel o, mounted on the rear part of the gage-shaft and meshing with a worm o' on the outer side of the flange H of the driving friction-disk F. The worm-wheel is connected with the gage-shaft by a clutch consisting of a coupling-pawl o², which projects through a slot o³ in the gage-shaft and into one of a series of recesses o⁴ in the bore of the worm-wheel. The coupling-pawl o² is pivoted in a recessed shifting rod o⁵, which slides lengthwise in the 110 hollow rear part of the gage-shaft and projects rearwardly through a bearing o⁶ in the rear side of the casing. Upon moving the shifting rod rearwardly by means of a finger-piece o⁷ at its rear end the coupling-pawl is 115 moved outwardly by a spring o⁸, so that it engages with the adjacent recess in the bore of the worm-wheel, and thereby couples the latter with the gage-shaft. Upon moving the shifting rod forwardly the coupling-pawl is 120 retracted or moved inwardly out of engagement with the recess in the worm-wheel by an incline o⁹ on the pawl engaging with an abutment o¹⁰ at the front end of the recess, thereby uncoupling the worm-wheel and gage-shaft. During the operation of tapping the gage-shaft is coupled with the worm-wheel. The gage-shaft n' is also connected with the tappet-wheel by a driving-clutch and a re-

125 130

turning-clutch. The driving-clutch at all times compels the tappet-wheel to turn forwardly with the gage-shaft, but permits the latter to turn backwardly without the gage-shaft. The returning-clutch compels the tappet-wheel to move backwardly with the gage-shaft from the stopping-place to a predetermined starting-place and then permits the gage-shaft to continue its backward movement independently of the tappet-wheel.

The forward driving-clutch of the tappet-wheel shown in the drawings, Figs. 8, 12, and 15, consists of a clutch-disk p , secured to the gage-shaft within the tappet-wheel, which is made hollow for the purpose, clutch-rollers p' , arranged in recesses p^2 , formed in the periphery of the clutch-disk p , and springs p^3 , which tend to move the rollers p' rearwardly in said recesses, so that they tend to grip against the inclined bottom of the recesses and the bore of the tappet-wheel.

The returning tappet-wheel clutch (shown in Figs. 8, 10, 11, 14, 15 and 19) consists of a clutch-disk Q , secured to the gage-shaft in front of the clutch-disk p and having peripheral notches q and a return clutch-pawl q' , pivoted at one end on the tappet-wheel and provided at its opposite end with a tooth q^2 , which is adapted to engage with the notches in the disk Q to couple the latter and the gage-shaft.

R represents a releasing-finger, whereby the return-pawl is disengaged from the return clutch-disk. This finger is arranged in front of the return-pawl and pivoted on the tappet-wheel concentric with the return-pawl. The free end of the releasing-finger is provided with an inwardly-projecting stop-lug r , which is adapted to bear against a circular bearing-face r' , formed on the return-disk in front of its notched portion. The return clutch-pawl q' and the releasing-finger R are arranged in a recess r^2 in the side of the tappet-wheel and are yieldingly pressed inwardly into their operative position by a spring r^3 , secured to the tappet-wheel and bearing against the outer side of the pawls. If desired, the return-pawl and releasing-finger may be made in one piece; but for convenience in manufacturing the same are made separate and are coupled by a pin or projection s on the return-pawl projecting into recesses s' in the outer side of the releasing-finger, whereby the latter when moved outwardly causes the return-pawl to be also moved outwardly.

T represents a dial or adjusting-head forming part of the gage mechanism, whereby the number of rotations of the tap is controlled. 60 This dial is capable of rotary adjustment in an opening formed in the front side of the casing concentric with the gage-shaft and is provided centrally with a bearing t , in which the front end of the gage-shaft is journaled. 65 The margin of the dial is provided with suitable graduations u , which coöperate with a mark u' on the casing, whereby the position

of the dial with reference to the other parts of the adjusting mechanism may be determined. The dial is secured to the casing and is also held in its adjusted position by means of a set-screw v , arranged in the casing and engaging with a peripheral groove v' in the dial, as shown in Figs. 4, 7, 11, and 15. The rear side of the dial is provided with a gage pin or stop w , which projects into the path of the releasing-finger R . When the releasing-finger and return-pawl are free and moved into their inner position, the releasing-finger inclines across the path of the gage-pin, as shown in Fig. 10.

In the rearmost position of the tappet-wheel the releasing-finger R engages with its inner side against the outer side of the gage-pin w and the rear side of the stop-lug r engages against the front side of the gage-pin, whereby the tappet-wheel is held against backward movement with reference to the gage-shaft and the releasing-finger and return-pawl are moved outwardly, so that the latter is out of engagement from the clutch-disk Q . The parts remain in this position and the gage-shaft is turned backwardly idly independent of the tappet-wheel so long as the casing is raised and the tap-actuating mechanism is connected by the reversing-gearing with the driving-spindle by reason of the coupling of the lower friction-disk F^2 and the reversing clutch-wheel L .

When the operator lowers the driving-spindle and the parts connected therewith until the tap bears against the article to be threaded and then continues to lower the driving-spindle and casing until the upper clutch or driving-wheel K is coupled with the lower clutch-disk J , as shown in Fig. 1, the tap commences to turn forward and cuts a thread in the article against which it bears and the gage-shaft is also turned forwardly. The instant the gage-shaft begins its forward movement the rollers p' of the driving-clutch grip against the inner side of the tappet-wheel and turn the latter forward with the gage-shaft. During the initial portion of this forward movement of the tappet-wheel the releasing-finger R is moved off from the gage-pin w and permits the spring r^3 to move the releasing-finger R and return-pawl q' inwardly on top of the reversing clutch-wheel Q and the whole gage mechanism moves forward as one until the tap or its support has made the predetermined number of rotations for which the gage mechanism has been set. During the last part of the forward movement of the tappet-wheel its tappet n is carried downwardly against the upper side of the trip-lug m^5 and moves the shipper-rod and clutch-disk J downwardly sufficiently to disengage the pins k^2 of the latter from the pins k' of the driving clutch-wheel K , as represented in Fig. 2, whereby the forward movement of the tap and tappet-wheel is arrested. The operator now raises the driving-spindle and the casing connected therewith, whereby the

coupling-pins b^3 of the lower clutch-wheel L are engaged with the coupling-pins b^4 of the lower friction-disk F ^{2} , as shown in Figs. 3 and 6, thereby connecting the tap at its support 5 through the medium of the reversing-gearing with the driving-spindle and causing the tap and the gage-shaft to turn backwardly. During the backward movement of the gage-shaft the rollers p' of the tappet-driving clutch do 10 not grip the tappet-wheel, but the latter is coupled with the gage-shaft by the return-pawl q' on the tappet-wheel engaging with the notched returning clutch-disk Q on the gage-shaft, whereby the tappet-wheel is turned 15 backwardly with the gage-shaft. The tappet-wheel moves backwardly with the gage-shaft until the releasing-finger R of the tappet-wheel engages with the stationary gage-pin w of the dial and is moved outwardly by the 20 latter sufficiently to disengage its companion return-pawl q' from the return clutch-disk Q, as shown in Fig. 19. When this takes place, the tappet-wheel is uncoupled from the gage-shaft and stands still, while the gage-shaft 25 continues to move idly backward until the operator again manipulates the apparatus for tapping the next hole.

The frictional contact between the gage-shaft and the tappet-wheel is prevented from 30 moving the latter backwardly with the gage-shaft by the rear side of the stop-lug r engaging with the front side of the gage-pin.

The number of forward turns which the tap or its support makes before its forward 35 movement is arrested depends upon the position of the gage-pin w with reference to the trip-lug of the shipper-rod, which is the stopping-place of the tappet-wheel. The tappet-wheel always moves forward from the gage-pin as a starting-place until its releasing-tappet uncouples the tool-support from the forward driving mechanism and then moves backwardly against the gage-pin. When the dial is adjusted so that its gage-pin is near to the 40 stopping-place of the tappet-wheel, the tap and its support will make only a few forward turns before being arrested, whereas if the gage-pin is moved farther away from the stopping-place of the tappet-wheel the tap will be 45 turned a correspondingly greater number of times before arrested in its forward movement.

If the tap should be arrested before completing its forward movement by striking the bottom of the hole which is being threaded 50 or by striking a hard spot in said hole, the driving-disk F would continue its forward movement independent of the tap and its support by slipping of the frictional connection between these parts. The driving-disk F continues to move forward after the tool has 55 been so arrested and operates the tappet-wheel until the latter has been turned forward the extent for which it was set and then uncouples the clutch-wheel K and disk J and stops the operation of the gage mechanism.

The graduations on the dial are arranged

according to the relative position of the gage-pin to the other parts of the gage mechanism, so that the operator can readily set the 70 apparatus for obtaining the required number of turns of the tap and a corresponding number of threads.

When it is desired to substitute a drill for boring a hole in place of the screw-thread 75 cutter or tap, the shifting rod o^5 is moved forwardly, so as to uncouple the worm-wheel O from the gage-shaft, whereby the gage mechanism is thrown out of gear. The dial is then turned so that its gage-pin w engages against 80 the front side of the lug r of the releasing-finger. The tappet-wheel is now caused to move backwardly with the dial until the tappet engages against the under side of the trip-lug m^5 and holds the shipper-rod and the 85 driven clutch-disk J up, so that the coupling-pins of the latter are engaged by the coupling-pins of the driving clutch-wheel K. Upon tightening the set-screw v against the dial while the parts are in this position the 90 clutch-wheel K and the clutch-disk J are locked in a coupled position and the drill which is attached to the holder or support is turned constantly forward.

Although I have shown my improved drilling and tapping attachment applied to a drill-press having a vertical driving-spindle, it is applicable to drill-presses having horizontal driving-spindles and other kinds of machines.

I claim as my invention—

1. The combination with a driving-spindle and a tool-spindle, of coöperating friction-disks arranged between the driving-spindle and the tool-spindle, an adjusting-sleeve movable lengthwise on one of said spindles 105 and connected with one of said friction-disks, a collar bearing against the adjusting-sleeve and having a screw connection with the spindle on which the sleeve is mounted, and a worm journaled on said collar and meshing 110 with worm-teeth on the adjusting-sleeve, substantially as set forth.

2. The combination with a driving-spindle and a tool-spindle, of a driving friction-disk connected with the driving-spindle, upper 115 and lower driven friction-disks engaging with opposite sides of the driving-disk, one of said driven disks being secured to the tool-spindle, an adjusting-sleeve splined on the tool-spindle and connected with the other driven disk, a collar having a screw connection with the tool-spindle, and bearing against the adjusting-sleeve, and an adjusting-worm journaled in said collar and meshing with worm-teeth on the adjusting-sleeve, substantially 125 as set forth.

3. The combination with a driving-wheel, and a tool-spindle, of a driving friction-disk, an upper driven friction-disk bearing against the upper side of the driving-disk and connected with the tool-spindle, a lower driven friction-disk bearing against the under side of the driving-disk, an adjusting-sleeve 130 splined on the tool-spindle and connected at

- its upper end with the lower friction-disk, an adjusting-collar having a screw connection with the tool-spindle and bearing against the lower end of the adjusting-sleeve, an adjusting-worm journaled in said collar and meshing with worm-teeth on the adjusting-sleeve, a clutch which connects the driving-wheel and driving friction-disk and whereby the tool-spindle is moved forwardly, a reversing-gearing which is arranged between the driving-wheel and the tool-spindle and whereby the latter is moved backwardly, and a clutch whereby said reversing-gearing may be rendered effective or ineffective, substantially as set forth.
4. The combination with a driving device, a tool-support, and a clutch whereby the driving device and tool-support are connected and disconnected, of a gage mechanism controlled by the rotation of the tool-support and which controls the movement of said support independent of the position of the work, substantially as set forth.
5. The combination with a driving-wheel provided with coupling-pins and a tool-spindle, of a clutch-disk which is connected with the tool-spindle so as to turn therewith but is capable of sliding lengthwise thereon and which is provided with coupling-pins adapted to engage the coupling-pins of the driving-wheel, a shipper-rod provided with a fork which engages with a peripheral groove in the clutch-disk, and a gage mechanism which is geared with the tool-spindle and which shifts the shipper-rod, substantially as set forth.
6. The combination with a driving-wheel provided with coupling-pins, and a tool-spindle, of a driving friction-disk provided with guide-pins, driven friction-disks connected with the tool-spindle and bearing against opposite sides of the driving-disk, a clutch-disk sliding on said guide-pins and provided with coupling-pins adapted to engage with the coupling-pins of the driving-wheel, springs arranged between the guide-pins and the clutch-disk, a shipper-rod provided with a fork which engages with a peripheral groove in the clutch-disk, and a gage mechanism which is geared with the tool-spindle and which shifts said shipper-rod and the parts connected therewith, substantially as set forth.
7. The combination with a driving-wheel provided with coupling-pins, and a tool-spindle, of a driving friction-disk provided with guide-pins, driven friction-disks connected with the tool-spindle and bearing against opposite sides of the driving-disk, a clutch-disk sliding on said guide-pins and provided with coupling-pins adapted to engage with the coupling-pins of the driving-wheel, springs arranged between the guide-pins and the clutch-disk, a stop device whereby the movement of the driven clutch-disk away from the driving friction-disk is limited, a shipper-rod provided with a fork which engages with a peripheral groove in the clutch-disk, and a

gage mechanism which is geared with the tool-spindle and which shifts said shipper-rod and the parts connected therewith, substantially as set forth.

8. The combination with a driving device, a tool-support, and a clutch whereby the driving device and tool-support are connected and disconnected, of a gage-shaft which is geared with said tool-support so as to move therewith, and a shipping device which is actuated by said gage-shaft and which shifts said clutch, substantially as set forth.

9. The combination with a driving-wheel, a tool-support, and a clutch whereby the driving device and tool-support are connected and disconnected, of a shipper-rod whereby said clutch is operated and which is provided with a trip-shoulder, a tappet-wheel provided with a tappet which is adapted to engage with said trip-shoulder and shift the shipper-rod, a gage-shaft connected with the tappet-wheel, and gearing connecting the gage-shaft with the tool-support, substantially as set forth.

10. The combination with a driving-wheel, a tool-support, and a clutch whereby the driving device and tool-support are connected and disconnected, of a shipper-rod whereby said clutch is operated and which is provided with a trip-shoulder, a tappet-wheel provided with a tappet which is adapted to engage with a trip-shoulder of the shipper-rod and shift the same, a gage-shaft which is geared with the tool-support, a forward driving-clutch which causes the tappet-wheel to turn forwardly with the gage-shaft, a return-clutch which causes the tappet-wheel to turn backwardly with the gage-shaft, and a stop or gage which controls the operation of the return-clutch, substantially as set forth.

11. The combination with a driving device, a tool-support, and a clutch whereby the driving device and tool-support are connected and disconnected, of a shipper-rod whereby said clutch is operated and which is provided with a trip-shoulder, a tappet-wheel provided with a tappet which is adapted to engage with said trip-shoulder and shift the shipper-rod, a gage-shaft which is geared with the tool-support, a forward driving-clutch which causes the tappet-wheel to turn forwardly with the gage-shaft, a return-clutch which causes the tappet-wheel to turn backwardly with the gage-shaft, and an adjusting-dial provided with a gage-pin which controls the operation of the return-clutch, substantially as set forth.

12. The combination with a driving-spindle, a tool-support and a driving-clutch whereby the driving-spindle and tool-spindle are connected and disconnected, of a shipper-rod whereby said driving-clutch is operated and which is provided with a trip-shoulder, a tappet-wheel provided with a tappet which engages with said trip-shoulder, a gage-shaft which supports the tappet-wheel and which is geared with the tool-spindle, a forward driving-clutch which causes the tappet-wheel to turn forwardly with the gage-shaft and

- which consists of a clutch-disk secured to the gage-shaft within the tappet-wheel and rollers which engage with inclines on the clutch-disk and with the bore of the tappet-wheel, a returning-clutch which causes the tappet-wheel to turn backwardly with the gage-shaft and which consists of a clutch-disk secured to the gage-shaft and provided with peripheral notches and a pawl pivoted 5 on the tappet-wheel and engaging with said peripheral notches, a releasing-finger connected with said pawl and provided with a stop, and a dial which is adjustable circumferentially with reference to the gage-shaft 10
- 15 and which is provided with a gage-pin adapted to engage with said finger for lifting said pawl out of the notched disk and to engage said stop for arresting the rotation of the tappet-wheel, substantially as set forth.
- 20 13. The combination with a driving device, a tool-support, and a driving-clutch whereby the driving device and tool-support may be connected and disconnected, of a gage mechanism which is geared with the tool-support 25 and which controls said driving-clutch, and a clutch whereby the gage mechanism may be rendered effective and ineffective, substantially as set forth.
14. The combination with a driving device, 30 a tool-support, and a driving-clutch whereby the driving device and tool-support may be connected and disconnected, of a gage mechanism which controls said driving-clutch and which is provided with a gage-shaft, a worm- 35 wheel mounted on said shaft and meshing with a worm which moves with the tool-support, and a clutch which connects and disconnects the gage-shaft and the worm-wheel, substantially as set forth.
- 40 15. The combination with a driving device, a tool-support, and a driving-clutch whereby the driving device and tool-support may be connected and disconnected, of a gage mechanism which controls said driving-clutch and 45 which is provided with a gage-shaft, a worm-wheel mounted on said shaft and meshing with a worm which moves with the tool-support, a shifting rod sliding in the gage-shaft, and a pawl mounted on the shifting rod and 50 projecting through a slot in the gage-shaft into a recess in the bore of the worm-wheel, substantially as set forth.
16. The combination with a driving device, 55 a tool-support, and a driving-clutch whereby the driving device and tool-support may be connected and disconnected, of a gage mechanism which controls said driving-clutch and which is provided with a gage-shaft, a worm-wheel mounted on said shaft and meshing 60 with a worm which moves with the tool-support, a shifting rod sliding in the gage-shaft, a pawl which is pivoted on said rod and which is pushed outwardly by a spring through a slot in the gage-shaft and into engagement 65 with a recess in the bore of the worm-wheel, and an abutment which is arranged at the end of said recess and which retracts said pawl from said recess by engaging with an incline on the pawl, substantially as set forth. 7c
17. The combination with a driving-wheel and a tool-spindle, of a driving friction-disk, two driven friction-disks connected with the tool-spindle and bearing against opposite sides of the driving friction-disk, an annular 75 flange projecting upwardly from the driving friction-disk, a supporting-ring secured to said flange and provided with guide-pins, a clutch-disk provided with openings which receive said guide-pins and with coupling-pins 80 which are adapted to engage with coupling-pins on the driving-wheel, springs interposed between said guide-pins and the clutch-disk, stop-screws which are connected with said supporting-ring and are adapted to engage 85 with shoulders on the clutch-disk, a shipper-rod connected with said clutch-disk, a tappet-wheel provided with a tappet adapted to shift said shipper-rod, a gage-shaft connected with the tappet-wheel, and a worm-wheel mounted 90 on the gage-shaft and meshing with a worm on the flange of the driving friction-disk, substantially as set forth.
18. In combination a tool-holder, a driving device, interposed clutch mechanism for rotating the former from the latter, and means for automatically throwing out said clutch independent of the axial movement of the holder relative to the driving device, substantially as set forth. 95 100
19. In combination a tool-spindle, a friction-disk carried thereby, a driving-spindle, a second friction-disk driven therefrom arranged in contact with and designed to drive the first disk, and clutch mechanism interposed between the driving-spindle and the second disk, substantially as set forth. 105
20. In combination a driving device, a tool-spindle, frictional driving mechanism interposed between the same, means for varying the frictional engagement of the members comprising said mechanism, and reversing mechanism interposed between the driving mechanism and said tool-spindle and operating independently of said means for varying the frictional engagement, substantially as set forth. 110 115
21. In combination a driving-spindle, a tool-spindle, means including a frictional disk interposed between said driving-spindle and tool-spindle for rotating the latter from the former, and gage mechanism operated from said disk, substantially as set forth. 120
22. In combination a driving-spindle, a tool-holder, interposed clutch mechanism, a shipper for throwing out said clutch, and an oscillating device located to one side and supported independently of the drive-spindle with means for operating the same for actuating said shipper, substantially as set forth. 125 130
23. In combination a driving-spindle, a tool-holder, interposed clutch mechanism, a shipper for throwing out said clutch, an oscillating device for actuating the shipper timed to

move in a predetermined relation to the rotation of said tool-holder and in unison therewith, said device actuating the shipper at the end of its stroke and means for varying the length of said stroke, substantially as set forth.

24. In combination a driving device, a tool-holder, interposed clutch mechanism for rotating the latter from the former, a shipper for throwing said clutch out, a device for operating the same, means for moving the latter during the rotation of the tool-holder, said movement being independent of the axial feed of the tool-holder, said device operating said shipper at a fixed point in its movement, and means for varying the distance between said fixed point and the point of starting of said device, whereby the time required for the device to travel from the starting position to the shipper may be varied, substantially as set forth.

25. In combination a driving device, a tool-holder, direct driving means including a clutch interposed between the driving device and said holder, reversing mechanism includ-

ing a clutch also interposed between the driving device and tool-holder, means for throwing out the first clutch including a controlling device having an oscillating movement with a variable stroke, said device operating to throw out the clutch at one end of its stroke, means for varying the opposite terminal of said stroke whereby the length of stroke is varied, and means for moving said controlling device in a predetermined time in relation to the rotation of said tool-holder.

26. In combination a tool-holder, a driving device and direct driving connections therefrom to said holder, means for automatically breaking said driving connection, and a rotatable dial adapted to be set manually for controlling said means, substantially as set forth.

Witness my hand this 19th day of January, 1901.

WILLIAM RUNGE.
